UNITED STATES PATENT OFFICE.

SAMUEL N. HALL, OF HOUSTON, TEXAS.

WELL-DRILLING MECHANISM.

1,030,533.

Specification of Letters Patent. Patented Jan. 14, 1913.

Application filed May 17, 1909. Serial No. 486,843.

To all whom it may concern:

Be it known that I, SAMUEL N. HALL, a citizen of the United States, residing at Houston, in the county of Harris and State of Texas, have invented a new and useful Improvement in Well-Drilling Mechanism, of which the following is a specification.

My invention relates to new and useful improvements in well drilling apparatuses 10 and more particularly to an apparatus for screwing and unscrewing pipe sections.

It is a well known fact that in drilling a well, the pipe is removed from the "hole" and replaced several times. Each time the 15 pipe is removed it is necessary to unscrew each section from the other, except where the derrick is high enough to take two or four sections, in which case only every second or fourth section is unscrewed. When 20 the sections are placed back in the "hole", they must be screwed together. Where the pipe is several hundred feet in length, this operation requires considerable time and labor.

5 The present method of screwing and unscrewing is to raise the joint above the rotary and by means of chain tongs connect or disconnect the sections; or by clamping one section with the guide rollers of the 10 rotary and holding the upper section with chain tongs. This latter method requires the rotating of the rotary in the opposite direction to its usual rotation and throws all the weight on the bearings of the rotary. 25 These methods are not only slow and laborious, but unsatisfactory, as the threads are often stripped and jammed.

My invention contemplates an apparatus 30 adapted to be attached to the frame of the rotary and operated by the driving mechanism of the rotary, while the latter is at rest. The screwing and unscrewing being accomplished by mechanical means without manual aid and in much less time.

45 The object of the invention is to provide such an apparatus, and one which will be strong, durable, efficient and simple, and comparatively inexpensive to produce and operate, also one in which the several parts 50 will not be likely to get out of working order.

With the above and other objects in view, the invention has relation to certain novel features of construction and operation, an 55 example of which is described in the speci-

fication and illustrated in the accompanying drawings, wherein:

Figure 1 is a side elevation showing the apparatus attached to an ordinary rotary, Fig. 2 is a transverse section taken on the line $\alpha-\alpha$ of Fig. 1 and looking in the direction of the arrow, Fig. 3 is a plan view of the apparatus, Fig. 4 is a plan view of the ratchet clamp, Fig. 5 is an elevation of the same and a portion of the pipe, Fig. 6 is a detail of the cam wheel, portions being broken away to illustrate the rollers, links and guide arms, Fig. 7 is a detail in section showing the wrench and its pawl, Fig. 8 is a plan view of a modified form of wrench 70 omitting the ratchet clamp, and Fig. 9 is a vertical section of the same.

In the drawings, the numeral 1, designates the bed frame of an ordinary rotary, 75 2 the driving shaft, 3 the driving sprocket, 4 the clutch, 5 the table and 6 the guide rollers. These parts may be of any approved construction and form no particular part of my invention.

At each side of the bed frame 1, uprights 80 7 are erected adjacent the table 5 and the driving sprocket 3. These uprights extend a short distance above the table and carry at their upper ends cross beams 8. This construction forms the support on which my 85 apparatus is mounted.

On each cross beam, a vertical end plate 9 is fastened. Parallel guide rods 10, arranged, two on each side and one above the other, have their ends secured in the end 90 plates. A drive shaft 11 is rotatably supported in the end plates and projects some distance beyond the outer plate, the parts being so positioned that the drive shaft 11 extends directly over the drive shaft 2 of 95 the rotary, which is placed substantially in the longitudinal center of the bed frame.

To impart a swinging movement to the wrench hereinafter described, a grooved cam wheel 12 having an extended hub 13 is 100 mounted on the shaft 11, being caused to turn therewith by means of an elongated key 14.

Guide frames are aligned with the wheel and its hub and comprise sleeves 15 adapted to slide on the rods 10, the sleeves on each side being connected by curved arms 16, as shown in Fig. 2. Referring to Fig. 6, as well as to Fig. 2, it will be seen that a space 110 is provided between each arm and the

grooved periphery of the cam wheel for the reception of a collar 17 loosely confined on a shouldered axle 18. Each axle is firmly fastened in the arm at the center thereof, 5 having its free end extending into the peripheral groove of the wheel where it supports a friction roller 19.

It is obvious that when motion is imparted to the cam wheel, the rollers operating 10 in the groove, will transmit a reciprocating movement to the guide frames, the sleeves 15 sliding on the rods 10.

Having described the means for swinging the wrench, the same and its component 15 parts will now be described.

After the pipe A has been drawn up, an ordinary "elevator" B is engaged about the pipe directly under the pipe collar C and rested on the guide rollers 6 as shown in 20 Fig. 1. It is to be understood that when the pipe sections are unscrewed, the collar is left on the lowermost section, the operation just described would be the same if the upper section was to be screwed into the collar 25 or unscrewed therefrom.

The wrench comprises two parts, a ratchet clamp 26 and a wrench member 21. The clamp is split, its parts being hinged together at one side and connected at the 30 other by an eye bolt 22 as shown in Figs. 4 and 5. This clamp is fastened about the pipe or the upper section just above the collar. Its lower portion is somewhat larger than the upper portion, which is provided 35 with vertical ratchet teeth 23, the lower portion providing a support and bearing on which the wrench member swings.

The wrench member 21 comprises a curved central portion 24 adapted to fit 40 around one side of the ratchet portion of the clamp and provided with oppositely extending radial arms 25. Opposite to the portion 24, a jaw 26 is hinged at one end and adapted to be held in position by a pin 45 27 passed through its opposite ends and the wrench member as shown in Fig. 3. When it is desired to place the wrench member on the clamp, or remove it therefrom, the pin is withdrawn and the jaw swung outward 50 permitting the wrench to be adjusted to the clamp and removed therefrom horizontally.

At the center of the jaw, a pawl 28 is pivoted on a post 29 as shown in Fig. 7 and adapted to engage the ratchet teeth 23 of the clamp. For holding the pawl in engagement with the teeth, the post which is shouldered, is extended above the jaw, and has fixed on its upper end, an arm 30 extending inward. A coiled spring 31 is secured to the end of the arm, while its free end is adapted to engage hook 32 at each side. The free end of the spring is engaged 60 with one hook to throw the pawl in the proper direction for unscrewing and to the other hook for screwing.

It is obvious that by swinging the wrench member about the clamp and its ratchet teeth, the pipe is turned and unscrewed from or screwed into the collar C, according to the position of the pawl. 70

The arms 25 are provided with a plurality of holes 33, which receive pins 34 carried in the ends of links 35, the pins being engaged in corresponding holes and the swinging of the wrench member being controlled by this engagement, being greater when the innermost holes are engaged. 75

Each link is pivotally connected, at its inner end, to one of the collars 17 and thus transmits the reciprocating or opposed 80 movement of the guide arms 16 and rollers 19 to the arms 25 of the wrench member. In the drawings, the cam wheel and wrench member are shown at their central or neutral point of their operation, it being understood that as the wheel revolves, the links are moved in opposite directions, their points of connection passing at the neutral 85 point of their movement.

It is apparent that the rapidity with 90 which the wrench member is swung and the pipe screwed or unscrewed, depends upon the speed at which the cam wheel is revolved. The cam wheel may be revolved at a fairly rapid speed and the screwing operation carried out in a very short time and very much faster than is possible with the methods now commonly in use. 95

For driving the cam wheel and its shaft 11, a sprocket 36 is loosely mounted on the 100 said shaft and provided with a clutch hub adapted to be engaged by a sliding clutch member 37 keyed on the shaft and operated by a lever 38 suitably supported from one of the cross beams. This sprocket is connected by a chain 39 with a sprocket 40 attached to the hub of the main driving sprocket 3. When it is desired to operate the rotary and not the screwing apparatus, the clutch 4 is thrown in and the clutch 37 110 thrown out and vice versa when the screwing apparatus and not the rotary is to be operated.

I desire to call attention to the fact that means utterly different from the cam wheel 115 may be employed to impart the desired swinging movement to the wrench member and I have designed other means for accomplishing this result, but consider that illustrated and described herein more satisfactory. The connections between the links and the arms and the guide arms and rollers may be changed, as well as the clamp and the wrench member tightened or strengthened or changed as the occasion may require. 120

It is to be understood that my apparatus is applied to the pipe section above the collar C and that it is necessary to hold the collar or the lower section of the pipe 125 130

against movement while my apparatus is in operation. This can be accomplished by any suitable means.

When it is not desired to use the apparatus, the jaw 26 is swung out after removing pin 27 and the guide sleeves 15 and cam wheel slid back on the rods 10 and the shaft 11; while suitable means for supporting the wrench is provided. The clamp is removed 10 by loosening the bolt 22.

I have found that it is possible to omit the ratchet clamp 20 and therefore in Figs. 8 and 9 have shown a modified form in which said part is omitted. In this case the wrench member 21 as well as the jaw 26 are provided with depending sleeve portions 42 adapted to embrace the pipe and support the wrench on the collar C. The pawl or dog 41 is substantially the same as the pawl 28 and its parts and their operation, except that the said pawl or dog 28 is provided with teeth 43 on its angular working edge, so that whichever way it is thrown, the teeth will bite into the pipe, and thus turn the latter 25 when the wrench is swung.

What I claim, is:

1. In a well pipe screwing and unscrewing apparatus, the combination with a suitable wrench adapted to surround and impart 30 rotary motion to a well pipe section, of means for imparting a rocking movement to the wrench, comprising, horizontal guides, guide frames mounted to slide on guides, links extending from the guide frames and 35 connected at their free ends to opposite sides of the wrench, and means for imparting a reciprocating movement to the guide frames.

2. In a well pipe screwing and unscrewing apparatus, the combination with a suitable 40 wrench adapted to surround and impart rotary motion to the well pipe section, of means for imparting a rocking movement to the wrench, comprising, a support, horizontal guides mounted in fixed relation on the 45 support, guide frames mounted to reciprocate on the guides, links pivoted to the guide frames and connected at their free ends with opposite sides of the wrench, a rotary device for imparting a reciprocating movement to 50 the guide frames, and means for imparting motion to the rotary device.

3. In a well pipe screwing and unscrewing apparatus, the combination with links and means for reciprocating the links in alternate relation, of a wrench having connection 55 at opposite sides with the free ends of the links and adapted to surround a well pipe section, and a spring held reversible member mounted on the wrench for imparting a

rotary motion to the well pipe section, the member being reversible independently of the wrench.

4. In a well pipe screwing and unscrewing apparatus, the combination with links and means for reciprocating the links in alternate relation, of a wrench having connection at opposite sides with the free ends of the links and adapted to surround a well pipe section, and a spring held pawl reversibly mounted on the wrench for imparting a rotary motion to the well section. 65

5. In a well pipe screwing and unscrewing apparatus, the combination with links and means for reciprocating the links in alternate relation, of a wrench having connection at opposite sides with the free ends of the links and adapted to surround a well pipe section, a pawl mounted on the wrench for imparting a rotary motion to the well pipe section, and a spring held arm connected to the pawl for reversing the same. 75

6. In a well pipe screwing and unscrewing apparatus, the combination with links and means for reciprocating the links in alternate relation, of a wrench having connection at opposite sides with the free ends of the links and adapted to surround a well pipe section, a pawl mounted on the wrench for imparting a rotary motion to the well pipe section, an arm projecting from the 85 pawl, projections on the wrench, and a spring connected to the end of the arm and adapted to engage either of the projections whereby the pawl is held under tension and may be reversed. 95

7. In a well pipe screwing and unscrewing apparatus, the combination with a suitable wrench adapted to surround and impart rotary motion to a well pipe section, of means for imparting a rocking movement to the wrench, comprising, a support, horizontal guides mounted in fixed relation on the support, guide frames mounted to reciprocate on and between the guides, links pivoted to opposite sides of the guide frame and connected at their free ends with opposite sides of the wrench, a shaft adjacent the guides, a projection on each guide frame, a cam wheel mounted on the shaft and engaging the projection, and means for imparting a rotary movement to the shaft. 100 105

In testimony whereof I have signed my name in the presence of two witnesses.

SAMUEL N. HALL.
